American Standard Inc., New York, N.Y.

Filed Aug. 2, 1973, Ser. No. 385,116

Term of patent 14 years

Int. Cl. D23—02

U.S. Cl. D23—62

FIG. 1

FIG. 4

FIG. 2

FIG. 3

FIG. 1 is a perspective view of a double bowl sink embodying my new design;

FIG. 2 is a top plan view thereof;

FIG. 3 is a cross-sectional view thereof taken along the lines 3—3 of FIG. 2; and

FIG. 4 is a cross-sectional view thereof taken along the lines 4—4 of FIG. 2.

The fragmentary broken line representation of a cabinet and the broken line representation of plumbing fixtures in FIG. 1 are for purposes of illustration only.

The characteristic feature of my design resides in the specific configuration of the flange extending from the bowls to the peripheral edge.

I claim:

The ornamental design for a double bowl sink, substantially as shown and described.
